AIR CONDITIONER

Clarence C. Hunicke, Palisade, N. J., assignor to
Auditorium Conditioning Corporation, a corpora-
tion of New Jersey

Application April 19, 1935, Serial No. 17,289

3 Claims. (Cl. 257—137)

This invention relates to apparatus for conditioning air.

In the conditioning of air wherein the temperature and humidity is controlled, one of the methods of removing humidity is to contact air to be conditioned with cold surfaces whereby condensation will take place, then by either reheat-
ing or mixing with warm air or recirculated air the temperature is raised the desired amount with
10 the desired relative humidity.

The general object of the invention is to pro-
vide an improved apparatus for conditioning air
by contact thereof with heat exchange means.

Still another object of the invention is to posi-
15 tively direct the current or currents of air in a
conditioner in predetermined paths or directions.

A further object of the invention is to control
the time of contact or the amount of contact of
the air to be conditioned with the conditioning
20 area.

A still further object of the invention is to
vary the amount of the air stream in contact
with the cooling medium to vary the air condition
of the air stream.

25 Referring to the drawing:

Figure 1 is a view in longitudinal section of a
device embodying the principles of my invention.

Figure 2 is a cross sectional view of Figure 1.

Figure 3 is a modified form of conditioning
30 device.

Figure 4 is a cross sectional view of Figure 3
along the line 4—4, looking in the direction of
the arrows.

In carrying out my invention, I propose to pro-
35 vide a conditioning chamber 1 having cooling
coils or cooling surfaces 2, 2', extending length-
wise of the conditioning chamber. The fresh air
is admitted through conduit 3 and the return or
recirculated air is admitted through conduit 4.
40 Three series of dampers control the admission
of fresh and return air to the conditioning cham-
ber 1. The dampers are separately controlled,
the top dampers being 6, the middle dampers 7,
and the bottom dampers 8. The control may be
45 either manual or automatic but is preferably
manual. Dampers 6, 7 and 8 control the flow of
air through the upper, intermediate and lower
portions of the conditioning chamber, and the
conditioning in the upper and lower portions may
50 be regulated by manipulation of dampers, 9, 10,
and 11, and 9', 10', 11'. For instance, if it is
desired to dehumidify the fresh air to a greater
degree than the return air, the dampers 9, 10
and 11, remain open, thereby permitting the
55 stream of fresh air to pass over the entire length

of the cooling surface 2 while the dampers 9', 10'
and 11' are closed, whereby return air passes over
only a portion of the cooling surfaces 2'. In
some cases the recirculated air may require greater
dehumidification in which event, dampers 9', 10'
10 and 11' may be presenting the full lengths
of the coils 2' to the recirculated air causing
greater cooling and condensation. These dampers
I preferably control automatically. The
dampers 9, 10 and 11, are controlled by a wet
bulb or hygrometer 12 and the lower dampers 9',
10', 11', by a thermostat 13. The controls 12
and 13 operate through the usual pneumatic sys-
tem. If desired, there may be separate controls
on each of the dampers in order to increase the 15
flexibility of the device. Chamber 34 forms a
mixing chamber and the proportion of mixing is
determined by the setting of dampers 6, 7 and 8.
That is, if dampers 6 and 8 are open while damp-
ers 7 are closed the mixing is the least and of 20
small amount.

Under certain conditions in the air space to be
conditioned, the lower dampers 8 may be closed
and the central dampers 7 opened as well as
dampers 6. In this case the return air will be 25
differently routed, that is, the major portion will
pass through the center of the apparatus and
thence through conduit 14 to the mixing chamber
15 from which the mixed airs are delivered. The
dampers 6 may be opened in varying degrees as 30
required and the fresh air will have full treat-
ment or be only partially treated depending upon
the automatic controls opening or shutting damp-
ers 9, 10 and 11, to route the fresh air either into
conduit 14 or lengthwise of conditioning surfaces 35
2. With a constant volume fan and the con-
striction of passage 14, the air will pass through
passage or conduit 14 with a higher velocity. As
the movement of the air is increased the time
and contact with the cooling surfaces is reduced. 40
With this apparatus a wide latitude of control
is established by the simple method of the control
by movable baffles of the direction of flow of the
air streams. If baffle 10 is separately controlled
the effect of the cooling coils may be increased or 45
decreased approximately one-third. In this way,
considerable sensitivity can be secured.

With my invention, under certain conditions,
artificial refrigeration is not required. If water
is obtained from a deep well so that the tempera- 50
ture is below fifty degrees, the proper condensa-
tion of the humidity can be obtained and the
cooling liquid is utilized at a constant tempera-
ture. Instead of varying the temperature of the
cooling liquid the length of time of contact with 55

the cooling surfaces is varied and the air to be conditioned is controlled with respect to its direction positively. The feature, of the control of the direction of the air being conditioned by 5 adjustable baffles, permits of an increased efficiency and a decrease in the initial costs as it avoids control valves for the coolant and reduces the amount of automatic controls; avoids the necessity of separate series of cooling surfaces 10 and makes certain a more positive control of the flow in the desired direction of the air being conditioned. Dampers 3', 4', control the proportions of fresh and return air.

In the modified form shown in Figures 3 and 4, 15 the central passage or conduit 14 is removed and the fresh or return air may be routed through conduits 16, 17, as desired to mixing chamber 15. The dampers 18 are each manually set whereby 20 the entering air streams may be controlled both as to volume and proportion, the latter by reason of stratification. Dampers 19, 20, 19', 20', are automatically controlled similarly as in Figure 1. In operation, the fresh air may require greater 25 dehumidification in which case dampers 19 and 20 will be open, closing aperture 21 and the return air, with dampers 19', 20', closed will pass through conduit 17 into mixing chamber 15. If it is necessary by reason of conditions the reverse 30 may take place and the fresh air may pass up through aperture 21 into conduit 16 and thence into mixing chamber 15.

The removal of moisture from air by surface cooling is dependent upon three elements, that is, 35 the area of the cooling surface in contact with the air, the time of contact and the temperature of the cooling surfaces. The control may be accomplished by variation of any one or more of the three means. By my invention, the area of contact of the cooling surface and the time of contact are varied by the directional control of 40 the flow of the conditioned air. If the cooling liquid is varied in temperature a longer time element is required and a more complicated and expensive system of refrigeration is necessary. 45 With my invention, artificial means of cooling may be dispensed with. A higher efficiency is accomplished as well as a control of the conditioning by the routing of the air streams. This control is more sensitive in that the baffles and 50 dampers are quickly adjusted while a time element is required to vary the temperature of the cooling liquid. Hence, where close temperature regulation is necessary such as in connection with the powder rooms on battleships and the like, 55 my invention is particularly adapted for use. Various modifications may be made and still fall within the principles of my invention.

What I claim is:

1. An air conditioning apparatus having a 60 conditioning chamber, a heat control unit in the conditioning chamber, means for supplying conditioning medium to said heat control unit, a

fresh air inlet, a return air inlet, means for circulating air from said different inlets past and in contact with different portions of said heat control unit, and a plurality of individually adjustable baffle means located between the discharge ends of said inlets and the heat control unit, different of said individually adjustable baffle means being located in the path of different portions of the air circulated in contact with said heat control unit, said baffle means being adapted to control individually the flow of fresh air and return air past and in contact with said different unit portions respectively. 5

2. In an air conditioning apparatus of the character described, the combination of means forming a casing, heat exchange means within said casing, means for passing air to be conditioned through said casing and successively in thermal contact with first one portion of said heat exchange means and then another portion of said heat exchange means, means forming a bypass passage adapted to receive air from said casing, said passage bypassing said other portion of said heat exchange means and communicating at its outlet end with the outlet end of said casing, and means including adjustable baffle means for delivering to said passage from said casing air which has been in thermal contact with said first portion only of said heat exchange means, whereby the extent to which air may be conditioned by 30 said apparatus may be controlled by routing air in contact with both portions of said heat exchange means or said first portion only thereof. 35

3. In an air conditioning apparatus of the character described, the combination of means forming a casing, heat exchange means within said casing comprising a first portion and a second portion, means for passing air to be conditioned through said casing and successively in thermal contact first with said first portion of said heat 40 exchange means and then with said second portion of said heat exchange means, means for receiving air delivered from said casing and means for delivering air which has been in thermal contact with said first portion only of said heat 45 exchange means to said air-receiving means in a course bypassing said second portion of said heat exchange means, said last-mentioned means including adjustable baffle means adapted to control said bypassing of air around said second 50 portion of said heat exchange means, whereby the extent to which air may be conditioned by said apparatus may be controlled by controlling said bypassing of air, greater conditioning effect being obtained by routing air in thermal contact 55 with both said first and said second portions of said heat exchange means and lesser conditioning effect being obtained by bypassing around said second portion of said heat exchange means air which has been in thermal contact with said first 60 portion only of said heat exchange means. 65
